UNITED STATES PATENT OFFICE.

JAMES HART ROBERTSON, OF NEW YORK, N. Y., ASSIGNOR TO ROBERTSON MOTOR FUEL PROCESS CORPORATION, A CORPORATION OF NEW YORK.

ART OF PRODUCING AND TREATING HYDROCARBON VAPORS DURING THE DISTILLATION OF THE SAME.

1,238,339.

Specification of Letters Patent.

Patented Aug. 28, 1917.

Application filed April 25, 1916. Serial No. 93,475.

To all whom it may concern:

Be it known that I, JAMES HART ROBERTSON, a citizen of the United States, residing at New York, and in the county and State thereof, have invented a new and useful Improvement in the Art of Producing and Treating Hydrocarbon Vapors During the Distillation of the same.

To this end my invention consists in the 10 electrical treatment of such vapors while the process of distillation is being effected.

My invention has for its most essential object, a more perfect decomposition of the combinations of the elements which form 15 the various vapors that result from the distillation of such oils, when heat and pressure alone were used and I effect this result by causing electricity to pass through the confined volumes of such gases, thereby obtaining results which have been found impossible in the practice of well known methods or processes.

For a full understanding of my invention, such as will enable others skilled in 25 the art to practice the same, reference is had to the accompanying drawings which disclose the apparatus used by me and in which Figure 1 is a diagrammatic view illustrating part of the apparatus in sectional view 30 and other parts thereof in side elevational view and Fig. 2 is a side elevational view of a modified form designed to operate upon oils for treatment where greater heat is required.

Fig. 3 is a cross section taken through the 35 line 3—3 of Fig. 2 and Fig. 4 illustrates a modification of the electrodes used in this form of the apparatus.

In practising the method or process embodied in my invention, the vapors are subjected to the action of an electrical current which may be either continuous or alternating and of high enough potential to produce disruptive effects on the vapors as they pass 45 under the influence of the current conveying electrodes inserted in the paths through which the vapors pass between the point of distillation and the condenser. These electrodes are preferably of such conveying area 50 as to give the best possible effects of the current upon the whole volume of vapors as they pass through the apparatus and there

may be as many of the same as thought best, the number thereof being optional.

Referring now to the drawings in details 55 and first to Fig. 1; *b*, is a blower driven by any source of power; 2, a tubular coil connected with the blower at one end and at the other to the main retort. 3, is a furnace, and 4, is the jacket of the main retort 60 6; 4', jacket of a second retort, 6'; 5, a partition in the center of the jacket of the main retort 5'; 6, the main retort; 6', secondary retort; 7, screw cap on main retort; 7', screw cap on secondary retort, 6'; 8, is 65 a pressure gage and 9 an insulating plug in the top of the main retort; 9' being a similar insulating screw plug in the top of the retort 6'. 10, a connection for the positive wire; 10' being a multiple connection for 70 said wire and both being connected directly to the dynamo. 11, is a graphite anode, electrically secured to connection 10; 11, is a similar anode, electrically secured to connection 10'. 12, feed vessel, 12' regulating 75 valve for hot air outlet; 14, valve above feed vessel and thirteen valve below the same; 15, air pipe connecting jacket of main retort 6 with jacket 4' of retort 6'; 16, pipe connecting inside of main retort with inside 80 of retort 6'. 17, containing vessel connected to the lower part of retort 6'; 20, pipe connecting the interior of the retort 6' with a condenser. 21, is condenser connected to the retort 6' by the pipe 20. 22, is a water 85 inlet for supplying water to the condenser; 23, is a water outlet therefor; 24, a receiving vessel for the products of condensation; 25, a valve between the condenser and the receiving vessel; 26, a pipe for the release 90 of permanent gases; 27, a valve connected with said pipe; *d*, is a separately excited dynamo; 29, rheostat therefor; 30, ammeter; 31, volt meter; 32, positive wire from dynamo connecting with the anodes 11 and 95 11' in multiple; 33, negative wire connecting the dynamo directly to the metallic surface of the condenser, 21.

Referring now to sheet 2 of the drawings, I will describe the modified form disclosed in Figs. 2, 3, and 4. 1, is the retort or still and 1—2 a feed pipe for the same; 1—3 a valve in the feed pipe; 2', furnace; 3" flue of furnace; 4" outlet of flue; 5" out-

let for residues from retort; 6", valve on same; 7" centering pins; 8", screw cap on the upper end of retort; 9", pipe leading to condenser (condenser not shown); 10", 5 valve on said pipe; 11", tubular electrode surrounded by retort; 12", tubular electrode plugged at either end and surrounded by electrode 11" and insulated from the same; 13" and 14", wires attached to the electrodes 10 and connected with the source of energy not shown; 15", rings of insulating material, placed on either end of electrode 11" for preventing the vapors from passing between the walls of the retort on the outer surface of 15 the electrode 11". The central electrode 12" is kept out of contact with the inner surface of the electrode 11" by means of insulating separator so placed as not to interfere with the passage of the vapors between the two 20 electrodes.

Fig. 3 is a cross section of Fig. 2 on the dotted lines 3—3; 1, being the retort; 3" the flue; 7" centering pins; 11" outer electrode; 12", inner tubular electrode, plugged at 25 either end and surrounded by electrode 11" and insulated from the same; 12'", an insulator, separating electrodes 11" and 12"; 15", rings of insulating material between the outer electrode and the inner walls of the 30 retort.

Referring now to Fig. 4 which illustrates a modification of the electrodes, 11" and 12" and consists of a tube split lengthwise, each half being insulated from the other which 35 allows of each electrode having an equal amount of surface 11" is one electrode and 12", the other and 12'", the insulating material separating the two from each other.

Referring now to Fig. 1, I will describe 40 the mode of operation of that form of the invention. The retort should be charged with material occupying a space between the bottom thereof and the lower part of electrode 11, as shown. After the different 45 valves have been closed, heat is introduced to the jackets, 4 and 4', from the heating coil, 2; the blower, b, having been started. Valve 12' on jacket 4' should be left open until the desired temperature is obtained, 50 after which it is partly closed so that just enough air escapes to allow a proper circulation through the jackets. After the vapor begins to form, the electric current is turned on and the voltage thereof gradually increased 55 until the amperage reaches the degree most suitable for the material being treated. The path of the heating current of heated air is as follows, through coiled pipe 2 in furnace 3, through jacket 4 to pipe 15 60 into jacket 4' and out, or if desired, back to the blower, b, by valve 12'.

This generates the hydrocarbon vapors in 65 the retort 6, and they pass out by pipe 16 into retort 6', passing thence out of said retort and by pipe 20, to the condenser, 21;

ultimately passing in liquid form out at the bottom thereof through valve 25 to receiving vessel 24, the permanent gases passing off through pipe 26 and valve 27 which is left open. The flow of the electric current 70 from the dynamo d is as follows; passing directly through the ammeter 30, wire 32, in multiple through the anodes 11 and 11', through the vapors to the walls 6 and 6' and back to the negative terminal of the dynamo 75 by way of pipe 20, condenser 21 and wire 33.

After the apparatus is heated to the desired degree, the feeding of further material can be arranged or adjusted without lessening the pressure by opening valve 13, 80 valve 14, being closed and letting a definite quantity thereof pass into the retort; or valve 13 may be adjusted so as to allow of a regular continuous feeding taking place. When the vessel 12 is being filled, valve 13 85 is closed and valve 14 is open. The vessel 17, beneath the retort 6', is, for convenience in tapping the contents, located at a point midway between the source of generation and the entrance to the condenser. The volt 90 meter 31, is bridged across wires 32 and 33.

In the form of apparatus shown in Fig. 2, the retort itself is located in the furnace and flue so that greater heat is generated and the operation of the apparatus is as 95 follows: the material being fed into said retort by the pipe 1—2, through the valve, 1—3 for controlling the feed, the heat passing upward from the furnace and around the retort in the flue 3" subjects the oil 100 to sufficient heat to vaporize it and these vapors pass upward between the outside of the electrode 12" and the inside of electrode 11" from whence it passes outward to the condenser not shown but by way of 105 the pipe 9" and valve 10" and ultimately to a chamber for receiving the completed product,—the electrical action from the electrodes 11" and 12" being the same as in Fig. 1.

Although I have described two modified forms of apparatus for practising the novel method hereinbefore described of electrically treating the vapors of hydrocarbon oils in such manner as to produce valuable 115 hydrocarbon vapors, such for instance as gasolene, I do not limit myself to these special devices for effecting such method as I believe it is broadly new with me to utilize as a reducing agent the effects 120 of an electrical current passing through a vapor of a hydrocarbon oil; nor do I limit myself to any special type of reduced product or result as I have ascertained that such vapors have a greatly increased value or 125 efficiency over existing types of vapors produced by well known methods and my claims hereinafter are therefore directed to the method or process hereinbefore described and broadly to mechanism for effecting such

method or process together with claims to the product produced by such method or process.

Having thus described my invention what 5 I claim and desire to secure by Letters Patent of the United States is—

1. The method of decomposing the heated vapors of crude oils which consists in causing an electrical current to be passed 10 through said vapors while the same are in compressed and heated condition.

2. The method of increasing the amount of gasoline obtained from the distillation of crude oil consisting in passing a disruptive current of electricity through the 15 heated vapor thereof while the process of distillation is being effected.

3. The method of changing the molecular condition of the vapor of crude oil so as to 20 increase the output of gasoline, consisting in subjecting the oil to heat and pressure sufficient to vaporize it and simultaneously passing a current of electricity through the vapor, thus produced; and finally condensing 25 the vapor thereby producing an electrolyzed liquid.

4. Apparatus for producing the vapors of crude oils embracing means for heating the same; means for vaporizing the heated oils 30 in compressed form; means for condensing said vapors, together with a source of electricity so arranged with relation to the foregoing means as to produce an electric

current passing through the volume of said vapors while in a heated condition. 35

5. An apparatus for producing gasoline, embracing a source of heat; one or more retorts for vaporizing crude oil; a condenser for reducing the vaporized oil to liquid form and a generator of electricity 40 connected in circuit with the interior of the retort or retorts in such manner as to subject the entire volume of the heated gases to the electrical influence of the current generated. 45

6. An apparatus for producing gasoline embracing a source of heat, as a furnace; a retort and means for supplying crude oil thereto; a condenser connected with the retort; a generator of electricity connected 50 in circuit with the interior of the retort, the electrodes of said retort being of relatively large surface area and located one within the other and adapted to electrolyze the gases produced by vaporization, together 55 with a receiving vessel adapted to store the completed product after it has passed through the coil of the condenser.

In testimony whereof I have signed my name to this specification in the presence of 60 two subscribing witnesses.

JAMES HART ROBERTSON.
